United States Patent Office.

JAMES VARLEY, OF HUDSON CITY, NEW JERSEY.

Letters Patent No. 81,847, dated September 1, 1868.

IMPROVEMENT IN WASH-BOILERS.

The Schedule referred to in these Letters Patent and making part of the same.

TO ALL WHOM IT MAY CONCERN:

Be it known that I, JAMES VARLEY, of Hudson City, in the county of Hudson, and State of New Jersey, have invented a new and useful Improvement in Wash-Boilers; and I do hereby declare that the following is a full, clear, and exact description of the same, reference being had to the accompanying drawings, forming a part of this specification, in which—

Figure 1 represents a vertical section of a wash-boiler constructed according to my improvement, and

Figure 2 represents a plan view of the same, with the lid or cover removed.

Similar letters of reference indicate corresponding parts in both figures.

This invention relates to wash-boilers, for cleansing clothing, and other fabrics of similar nature, and it consists in providing the boiler with a central-jointed tube, projecting from a perforated false bottom, and communicating with an upper chamber with perforated bottom, whereby a current or rapid water circulation is established in the boiler, and a more general distribution of the boiling water produced on and through the clothing or other articles; by the generation of steam therein; and it furthermore consists in providing the upper chamber with a vertical adjustment, by means of a telescopic or sliding joint in said tube, whereby the elevation or depression of the upper chamber will afford more or less ventilation, as may be desirable, to insure more or less rapidity of circulation within the boiler, and through the fabrics therein contained. It furthermore consists in providing the false bottom with an effectual means of resisting the upward pressure of the steam from beneath.

In order that others may be enabled to understand the construction and operation of my invention, I will proceed to describe it with reference to the drawings.

A is a boiler, of circular formation, and constructed of any suitable material. At or near the bottom of this boiler is a false bottom, B, of an upward convexity of form, having perforations, b b, near its outer edge, for the passage of the cooler water to the bottom of the boiler A. This false bottom, B, is kept to its place by lips p p, attached to the inner wall of the boiler A, which act against the edge of the false bottom in such manner as to hold it down when the steam acts against the under side thereof, but is provided with notches, e e, cut in its edge, large enough to pass over the said lips p p, so that when it is desirable to remove the false bottom, for cleaning or any other purpose, by turning it so as to bring said notches directly opposite to and under the said lips or projections p p, it may be readily removed.

C is a vertical tube, through which is provided an upward passage for the hot water from below the false bottom when it is forced upward by the generation of steam, and has its lower extremity secured to the central portion of the false bottom, B, so as to communicate through the same with the space below, and, passing centrally through the boiler A, communicates with an upper chamber, D, situated within the lid or cover of the boiler, and passing through its bottom, and terminates about the centre of the said chamber D.

This chamber D in the lid or cover is constructed by simply providing the same with a suitable bottom, d, through which the tube C passes, and to which it is secured, and which said bottom, d, is perforated with small openings or perforations, e, over its entire surface, for the downward passage of the water which overflows the tube C. The tube C is supplied with a telescopic or sliding joint, a, at or near its central portion, which not only provides for the entire removal of the lid or cover for insertion or removal of the articles to be cleansed, or for other purpose, but also for effecting a means of ventilation to the boiler during the process of cleansing, by a slight elevation of the cover, and by thus giving more or less elevation to the same, the said ventilation may be regulated to any desirable degree.

In the operation of this invention, the fabrics or articles to be cleansed are placed within the boiler A, upon the false bottom, B, and around the tube C, and a sufficient quantity of water poured into the boiler to completely immerse the fabrics, when the cover is placed thereon, so that the upper portion of the tube C will fit and slide over the lower portion thereof. The said cover is not closed entirely down, but a slight opening is left between it and the edge of the boiler, for the purpose of giving more variation or difference of temperature

between the water above and that below, so as thereby to increase the rapidity of the circulation. The heat is applied, in the usual manner, at the bottom of the boiler, and as soon as the water begins to boil, it rises, and, passing up through the tube C, overflows the same. Simultaneously with this rise and overflow of the boiling water, the cooler water above the false bottom is supplying its place through the perforations or openings *b b* of said false bottom, and, in turn, the boiler A is being supplied with a like quantity from the upper chamber, D, through the perforations *c* of its perforated bottom, *d*, and thus a continuous current is kept up through the boiler A and the articles therein contained.

What I claim as my invention, and desire to have secured by Letters Patent, is—

1. The central-jointed tube C, perforated upper chamber D, and false bottom, B, in combination with each other and with a wash-boiler, substantially as herein described.
2. The telescopic or sliding joint *a*, in combination with the central-jointed tube C, for adjustment of the upper chamber D, or removal of the cover, substantially as herein set forth.
3. The combination of the lips *p p* and notches *e e*, for locking in place the false bottom of the wash-boiler, substantially as specified.

JAMES VARLEY.
